UNITED STATES PATENT OFFICE.

CHRISTIAAN KRÄMER, OF BRUSSELS, BELGIUM.

DESIGN FOR A CARRIAGE-BODY.

No. 37,731.

Specification for Design.

Patented Dec. 12, 1905.

Application filed June 28, 1905. Serial No. 267,455. Term of patent 7 years.

To all whom it may concern:

Be it known that I, CHRISTIAAN KRÄMER, a subject of the King of Belgium, residing at Lacken, Brussels, Belgium, have invented a new, original, and ornamental Design for Carriage-Bodies, of which the following is a specification, reference being had to the accompanying drawing, forming part thereof.

The figure is a perspective view of a carriage-body, showing my design.

I claim—

The ornamental design for a carriage-body as shown.

CHRISTIAAN KRÄMER.
